UNITED STATES PATENT OFFICE.

GEORGE M. HANNON, OF BELTON, TEXAS.

FLY-KILLING DEVICE.

1,340,767.

Specification of Letters Patent. Patented May 18, 1920.

Application filed October 11, 1919. Serial No. 329,932.

To all whom it may concern:

Be it known that I, GEORGE M. HANNON, a citizen of the United States, residing at Belton, in the county of Bell and State of 5 Texas, have invented new and useful Improvements in Fly-Killing Devices, of which the following is a specification.

The object of my present invention is the provision of a device designed more especially for killing or "swatting" flies on the ceiling or high portions of the side walls of an apartment; the device being simple and inexpensive in construction, but with its parts so relatively arranged that the killing 15 blade may be quickly struck against a ceiling or a wall by a person standing on the floor of the apartment.

Other practical advantages of the invention will be fully understood from the following description and claims, when the same are read in connection with the drawings, accompanying and forming part of this specification, in which:

Figure 1 is a face view of the killing device or "swatter" constituting the best practical embodiment of my invention of which I am cognizant.

Fig. 2 is an elevation taken at right angles to Fig. 1.

Fig. 3 is an enlarged cross-section taken through the blade of the device in the plane indicated by the line 3-3 of Fig. 1.

Fig. 4 is a view diagrammatic in character and illustrating the capacity of the 35 blade of the device to assume a position flatwise against the ceiling of an apartment.

Similar numerals of reference designate corresponding parts in all of the views of the drawings.

The blade of my novel "swatter" is made up of a frame 1, carrying a section of screen wire 2 and covered with rubber or its equivalent 3, with a view to precluding the possibility of the blade scratching or marring 45 furniture or wall paper.

In addition to the blade, my "swatter" comprises a handle 4, a slender and highly resilient shank 5 and an arm 6, carried by the handle 4 at the same end as the shank 5 and having an eye 7 that loosely receives the 50 said shank 5 with a view to enabling the blade to strike flatwise against a ceiling or

wall irrespective of the angle at which the handle 4 is manipulated. See in this connection Fig. 4. The handle 4 is preferably about three feet in length, and for the sake of lightness is made of a piece of cane, although other light material may be resorted to without affecting my invention. A thimble 8 is suitably secured on one end of the handle 4, and the shank 5 is fastened by means of said thimble in the end portion of the handle. It will be noticed in this connection that the arm 6 is joined to the shank 5 through the medium of a long loop 9, and that the said loop, formed in part by the shank 5, is socketed in the thimble and the handle 4. It will also be noticed that the eye 7 on the arm 6 enables the blade to assume various angles to the handle 4 by reason of the shank 5 being adapted to play freely through the eye, and that when the blade is relieved of pressure or stress, the eye 7 by acting upon the shank 5 assures the return of the blade to its normal position—
i. e., in alinement with the handle.

In using my novel device, a person standing upon the floor of the apartment strikes the blade against the ceiling after the manner shown in Fig. 4, and from this it will be appreciated that my novel device is highly efficient in so killing flies. It will also be appreciated that by reason of the construction described, the person using the device is enabled to strike quickly and surely.

Having described my invention, what I claim and desire to secure by Letters Patent, is:—

1. A fly killing device comprising a handle, a blade spaced from one end of the handle, a resilient shank on the blade, and a resilient arm having an eye that loosely receives the shank; said shank and arm being joined by a relatively long loop that is socketed in the end portion of the handle.

2. A fly killing device comprising a handle, a blade spaced from one end of the handle, a resilient shank interposed between and connecting the blade and one end of the handle, and an arm connected to said end of the handle and having an eye that loosely receives said resilient shank.

In testimony whereof I affix my signature.

GEORGE M. HANNON,
